US0D1092964S

(12) United States Design Patent (10) Patent No.: US D1,092,964 S
(45) Date of Patent: * Sep. 16, 2025

(54) SUITCASE

(71) Applicant: LOUIS VUITTON MALLETIER,
Paris (FR)

(72) Inventor: Clément Logereau, Paris (FR)

(73) Assignee: Louis Vuitton Malletier, Paris (FR)

() Term: 15 Years

(21) Appl. No.: 29/918,709

(22) Filed: Nov. 29, 2023

(51) LOC (15) Cl. 03-01

(52) U.S. Cl.

USPC D3/279; D3/276; D3/289
